CLAIM

The ornamental design for a manual pole saw as shown and described.

DESCRIPTION

FIG. 1 is a perspective view of a manual pole saw showing our new design;

FIG. 2 is another perspective view thereof;

FIG. 3 is an enlarged collapse state diagram;

FIG. 4 is another enlarged collapse state diagram;

FIG. 5 is a front view thereof;

FIG. 6 is a back view thereof;

FIG. 7 is a left view thereof;

FIG. 8 is a right view thereof;

FIG. 9 is an enlarged top view thereof;

FIG. 10 is an enlarged bottom view thereof;

FIG. 11 is an enlarged view taken from indicated area 11 of FIG. 1;

FIG. 12 is an enlarged view taken from indicated area 12 of FIG. 1;

FIG. 13 is an enlarged view taken from indicated area 13 of FIG. 2;

FIG. 14 is an enlarged view taken from indicated area 14 of FIG. 2;

FIG. 15 is an enlarged view taken from indicated area 15 of FIG. 5;

FIG. 16 is an enlarged view taken from indicated area 16 of FIG. 5;

FIG. 17 is an enlarged view taken from indicated area 17 of FIG. 6; and,

FIG. 18 is an enlarged view taken from indicated area 18 of FIG. 7.

The broken lines showing of the indication boxes and forms no part thereof. The remaining broken lines shown in the drawings depict portions of the manual pole saw that form no part of the claimed design.
